Primary Examiner — Daniel Bui(74) *Attorney, Agent, or Firm* — Robert J. Ireland(57) **CLAIM**

The ornamental design for an electrical plug housing, as shown and described.

DESCRIPTION

FIG. 1 is a front, top, and right side perspective view of an electrical plug housing showing our new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a back elevation view thereof; and,

FIG. 7 is a front elevation view thereof.

The broken-line in the drawing views represent unclaimed environment only and forms no part of the claimed design.

1 Claim, 7 Drawing Sheets(56)
